UNITED STATES PATENT OFFICE.

JAMES R. FLANIGAN, OF BOSTON, MASSACHUSETTS.

DESIGN FOR MEDAL-BATTERIES.

SPECIFICATION forming part of Design No. 11,656, dated February 24, 1880.

Application filed January 19, 1880. Term of patent 7 years.

To all whom it may concern:

Be it known that I, JAMES R. FLANIGAN, of Boston, in the county of Suffolk and State of Massachusetts, have invented and produced a new and original Design for a Medal-Battery, of which the following is a specification, reference being had to the accompanying drawing, forming part thereof.

Figure 1 is a perspective view of a medal-battery, which fully illustrates my design.

The leading feature of my design consists in a scalloped disk of copper located centrally and surrounded by a series of zinc, copper, and brass disks of two sizes, the larger ones uniting two of the scallops of the central copper disk, and the smaller ones uniting with the largest diameter of the central copper disk, and also with the two larger disks at each side of such smaller ones, their relative positions being a larger disk of copper, a smaller one of zinc, a larger one of brass, a smaller one of copper, a larger one of zinc, a smaller one of brass, a larger one of copper, a smaller one of zinc, a larger one of brass, a smaller one of copper, a larger one of zinc, a smaller one of brass, thus completing a circle the outer diameter of which is surrounded by a narrow band or ring of German silver, which contacts with each disk, forming a circular medal-battery, two of which are placed together flatwise, with a piece of red flannel interposed between, and which may be seen through the

open spaces intervening between the edges of the several disks at the points where they do not contact, these two medal-batteries being secured together by a central pin, of ivory or other non-conducting material, thus presenting to the eye the combined effect illustrated by the drawing, wherein the light central circular portion is ivory, surrounded by the scalloped disk of copper, which disk is surrounded by the four circular disks of zinc represented by circular lines, the four copper disks represented by right-angled lines, and the four brass disks represented by the star lines with a black center, the red flannel being represented by the mottled spaces, and the inclosing-ring, of German silver, being represented in white.

I claim—

The design for a medal-battery herein shown and described, the same consisting of the scalloped central portion of copper, surrounded by the circular disks of zinc, copper, and brass, which disks are inclosed by the circular ring or hoop of German silver, forming a medal, two of which are placed flatwise together, with a piece of red flannel interposed between, and held in position by the central pin, of ivory or other non-conducting material.

JAMES R. FLANIGAN.
